THERMIONIC AMPLIFIER

Cecil Oswald Browne, Ealing Common, London, England, assignor, by mesne assignments, to Radio Corporation of America, New York, N. Y., a Corporation of Delaware

Application October 23, 1929, Serial No. 401,930,
and in Great Britain November 17, 1928

5 Claims. (Cl. 179—171)

The present invention relates to thermionic amplifiers and has as its object the provision of an amplifier of small size, great simplicity and high magnification at acoustic or audio frequencies.

According to the present invention an audio frequency thermionic amplifier, for example for use in recording sound or in the reproduction from a sound record, comprises a four electrode valve immediately followed by a five electrode valve or pentode.

The invention is illustrated by way of example in the accompanying drawing.

In the drawing the first valve V_1 is a four electrode valve commonly known as a screened grid valve. The inner grid 1, or that nearer the filament 2, is connected to one input terminal 3 through a condenser 4, the other input terminal 5 being connected to the filaments 2, 6 of both valves V_1 and V_2 . The usual grid leak 7 is provided and the inner grid 1 may, through the leak, be given a negative bias of about 2 volts with respect to the filament. The outer grid 8 may be given a potential of about 75 volts positive with respect to the filament 2. The anode 9 of the valve V_1 is connected through an iron-core choke 10 with a suitable potential of substantially 150 volts. The anode 9 is connected through a condenser 11 with the inner or control grid 12, of a five element valve V_2 of the type known as a pentode, a grid leak 13 being provided through which this grid is given a negative bias with respect to the filament 6, of about 14 volts. As characteristic of the pentode type of valve, the outer grid 14 of the pentode V_2 is connected to the filament 6 and the intermediate grid 15 may be supplied with a suitable positive biasing potential.

The anode 16 of the pentode V_2 is connected through the primary winding of an output transformer 17 to a suitable current source of about 150 volts. It will be noted that since this is the same potential as required for the anode circuit of the screen grid valve V_1 , the two circuits may be connected with the same source of supply, as indicated in the drawing. This is a relatively low voltage and is permissible with the amplifier arrangement shown in the drawing, comprising a pentode or stabilized low voltage power output valve, impedance coupled with a high gain voltage amplifier employing a high impedance stabilized valve such as a screen grid valve. This amplifier arrangement is therefore relatively simple and effective both in gain and quality and is economical of voltage,

since both valves are adapted to be connected to the same low voltage supply source. The secondary winding of the transformer 17 may be connected with any suitable output device or circuit, not shown.

The amplifier illustrated is adapted for use in reproducing sound from a photographic sound record, the terminals 3, 5, being adapted to receive the electrical input therefrom. For this purpose the resistance 18 and the potential divider 19 are preferably provided in known manner.

It should be noted, as obvious to one skilled in the art, that an amplifier of the character above described, employing two high gain valves, not only provides for a relatively high amplification of the input signals and hence may have a relatively high sensitivity with a relatively low current drain upon the anode potential supply source, but also has a desirable frequency response characteristic whereby it is particularly well adapted for use with known sound producing devices such as loud speakers for example. This is for the reason that, as is well known, loud speakers and the like are more sensitive in the higher frequency end of the audio frequency range and therefore tend to provide a greater response in the higher frequency range. The pentode type of tube, however, tends to reduce the high frequency response because of the shunt capacity imposed by it across the circuit, between its input electrode and cathode, thereby tending to compensate for the response characteristic of a device connected in its output circuit. Both devices being of the screen grid or stabilized type also tends to improve the transmission characteristic of the amplifier by eliminating feed-back through the inter-electrode capacity of the devices.

The amplifier may however, be used in conjunction with a wireless receiver, a detector being connected or coupled to the control grid circuit of the valve V_1 .

I claim:

1. The combination, in an audio frequency amplifier, of a screen grid high impedance input valve, impedance coupling means providing an input circuit therefor, a second impedance coupling means providing an output circuit therefor, a power output valve of the pentode type connected with said output circuit whereby said valves are impedance coupled, and adapted to operate in connection with a common low voltage source of anode current, and means adapted

to provide a common low voltage source of operating potentials for said valves at values providing relatively low current consumption and relatively high power output in response to signal potentials of relatively low amplitude.

5 2. In an audio frequency amplifier having input and output terminals, means providing a relatively high signal gain from said input terminals to said output terminals and a frequency 10 compensation characteristic, said means including a first stage high impedance screen grid valve having a relatively high amplification constant connected with said input terminals, a second stage valve having a relatively high amplification constant connected with said output terminals, and impedance coupling means interposed between said valves whereby they are connected in cascade relation to each other in said amplifier, said second named valve being of the 15 low anode voltage, pentode type, and having input electrodes arranged to provide a high frequency attenuating capacity in shunt to a portion of the amplifier circuit.

3. In an audio frequency amplifier, the combination of a pair of valves each having a relatively high amplification constant, and impedance coupling means interposed between and connecting them in cascade relation, whereby said valves provide a first and a second stage 30 of said amplifier, said first stage valve being of the screen grid type whereby it is adapted to be connected with said impedance coupling means and operated in response to low potential signals, and said second stage valve being of the low voltage, pentode type, whereby it imparts a frequency attenuating characteristic to

the audio frequency amplifier in a higher frequency portion of the audio frequency range.

4. In an audio frequency amplifier, the combination with a low voltage power output valve of the pentode type adapted for relatively high signal amplification, and power output, at low operating and signal potentials, of means for driving said valve in response to relatively low signal potentials and with relatively low operating potentials and current, including a screen grid high impedance valve adapted to receive signal impulses, and impedance coupling means connected between said last named valve and the output valve for transmitting amplified signal impulses to said output valve, said amplifier being thereby stabilized and sensitive to signals of relatively low amplitude.

5. The combination, in an audio frequency amplifier, of a screen grid high impedance input valve, impedance coupling means providing an input coupling network therefor, a second impedance coupling means providing an output circuit therefor, a power output valve of the pentode type connected with said output circuit whereby said valves are impedance coupled and adapted to operate in connection with a common low voltage source of anode current, means adapted to provide a common low voltage source of operating potentials for said valves at values providing relatively low current consumption and relatively high power output in response to signal potentials of relatively low amplitude, and means providing a circuit connection between said input coupling network and said last named means.
